UNITED STATES PATENT OFFICE

2,581,825

CLASP

Ah Fong Lau Ah You, Honolulu, Territory of Hawaii.

Application February 14, 1946, Serial No. 647,623

1. Claim. (CL 24—3)

1. This invention relates to key and key chain holders.

The principal object of the invention is the provision of a holder of the character described which may be locked to the trouser belt or other support to prevent accidental displacement thereof and consequent loss of the keys carried by it.

Another object of the invention is the provision of an article of the character described which may very readily be hung upon the trouser belt and equally as readily removed therefrom.

A further object of the invention is the provision of an article of the character described which is of simple construction, easily made of few inexpensive parts.

A preferred embodiment of the invention is shown in the accompanying drawing in which:

Fig. 1 is a side view of the device showing it in open position;

Fig. 2 is a view similar to that of Fig. 1, partly broken away, to show the device in closed or locked position; and

Fig. 3 is a perspective view of the three parts comprising said device, showing said parts separate from each other.

The device herein claimed comprises a supporting member 10 by which the holder as a whole is supported from a trouser belt or other support, a locking member 11 which performs two functions, one being to lock the supporting member 10 on the belt and the other being to carry the third member of the device, to wit, a ring 12 which may be used to carry the keys proper or a key chain.

Reference to Fig. 3 will show that the supporting member 10 comprises a U-shaped member of which one leg 15 is longer than the other leg 16. At the end of leg 16 is an aperture 17 to permit the locking member 11 to be pivoted to this leg. This U-shaped member is made preferably of spring steel to render it possible to spread the legs apart as will hereinafter be mentioned, and yet to have these legs return to their original position. This member may, of course, be made of any other suitable material such as plastic material.

The locking member 11 is in the form of a plate which at one end is looped as at 20 to receive the ring 12 and at the other end is bent back on itself to form a folded portion having loops 21 and 22 at its ends. The folded portion thus formed acts as a link pivoted at loop 21 to the end of leg 16 and its length is greater than the normal distance between the legs 15 and 16.

2. This invention relates to key and key chain holders.

2. through the pivot point and at right angles to both legs. The rest of the plate 11 acts as a handle to operate the link and to support the ring 12. An aperture 18 is formed in the leg 15 to one side of this rectangular line and acts as a recess or notch to receive and latch the link in a definite position by means of the loop 22 when the link is swung around its pivot point to direct its slope to the right as viewed in Figure 1.

10. It will be noted in the drawing that the locking member 11 is hinged to the supporting member 10 in the following manner: The middle loop 21 is looped around the bar 19 which is formed at the very end of the short leg 16 of the supporting member 10. When the locking member 11 is thus hinged to the supporting member 10, it will be seen particularly in Fig. 2 that the loop 20 abuts the lower end of long leg 15 and the loop 22 enters the opening 18 of said long leg 15. To remove the loop 22 from the opening 18 and thereby to open the supporting member 10, the locking member 11 is pushed or pulled to the position shown in Fig. 1.

25. The ring 12 may be of any conventional construction and of any desirable material and it is pivoted to the loop 20. The two ends 30 of said ring 12 serve as the pivot proper and the loop 20 serves as the socket for said pivot. As a practical proposition, the device hereinabove described may be locked by simply grasping the ring and pulling it to the position shown in Fig. 2 and the device may be unlocked by pulling said ring to the position shown in Fig. 1. The ring may be used to carry keys or it may be used to carry a chain for keys or a watch or similar articles.

30. As viewed in Figure 1, when the link is disposed in a position directed to the left of the rectangular line above mentioned, the device is unlocked and when the link is disposed in a position directed to the right of said line the device is locked and a belt or other element held between the link and the end of the U between the legs 15 and 16 can not move out and the more this is tried, the more the link is forced into locking engagement 45 in the aperture 18. As will be apparent, as the plate 11 is swung to the left from the position shown in Figure 1, the link will move to the right and because of its length will spread the legs apart as it reaches this rectangular position after which the legs will snap toward each other and the loop 22 or end of the link will be forced by the resiliency of the legs into the aperture 18 and will be held therein. Therefore, it is clear that a simple pull on the ring 12 in one direction or the other will lock and unlock the device 50.

and the weight of the ring and the elements supported thereon will keep the device locked when it is supported on a belt or similar support.

It will be understood that the foregoing is but a preferred embodiment of the invention and it may be modified in different ways without departing from the basic principles of the invention. For example, this invention has above been described as relating principally to key and key chain holders. Actually, this invention may be used in a number of different ways as, for example, a paper clamp or a clamp used in any other similar connection.

I claim:

A holder including a pair of legs of a resilient U-shaped member, a lock link pivoted at one end to one leg and of a length greater than the normal line between the legs drawn through the pivot point, the other leg having a latching recess therein on the side of said normal line toward the base of the U-shaped member, said recess adapted to receive the unpivoted end of said link, the resiliency of the legs holding the unpivoted end of the link in the recess after the link has been swung past the normal line toward said recess and said link then being disposed between

the legs, an operating plate connected at one end to said link to move it one way or the other, and a key ring pivotally connected to the other end of said plate.

AH FONG LAU AH YOU.
